WOOD CORE METAL-SHEATHED DOOR

Eugene O. Olsson, Minneapolis, Minn.

Application June 23, 1949, Serial No. 100,811

1 Claim. (Cl. 20—35)

1

This invention relates to wood core metal sheathed doors and particularly to a door with an attractive appearance, suitable for modern store fronts, and of substantial construction though economically manufactured.

Much has been done in the field of doors, but there is still lacking a door that is in keeping with modernistic store front designs, and that can be provided of substantial construction at a reasonable cost. Several different hollow metal door constructions have been devised, but to meet the requirements, complicated construction involving trussing, interlocking tongues and channels, and quite heavy metal to prevent denting is necessary, so that the cost becomes excessive. Some wood doors with a full or a partial metal covering have been provided, but have not met with much favor for use for front entrance doors for stores and business places. There is a need for a door, constructed of materials to provide a fine surface finish, and having properties comparable to an all metal hollow door, but which can be produced at a much lower cost.

An important object of my invention is to provide a wood core, metal sheathed door by a construction, which eliminates any need for welding, which, if not impossible, would damage the finish on desirable metal surfaces.

Another important object is to provide a construction by which all joints are concealed, so that the door has the appearance of an all metal door.

Another object is to provide such a door, which although of substantial and solid construction, can be economically manufactured.

Other objects will be apparent from the description and appended claim.

For a full disclosure of my invention, reference is made to the description following and to the drawings, in which—

Fig. 1 is an elevational view of an upper corner of the door showing the joining of top rail and stile.

Fig. 2 is a sectional view of the stile, taken on the line 2—2 of Fig. 1, showing the manner in which the metal sheathing is secured to the wood core, and combining therewith the moldings for engaging a glass panel.

Fig. 3 is a sectional view of the top rail, taken on the line 3—3 of Fig. 1, which in addition to the details shown in Fig. 2, shows the manner in which the metal sheathing is secured at the top edge of the door, and how a flush construction is provided by an inverted channel.

Fig. 4 is a top view of the door, with the in-

verted channel removed, and with a part of the view in section, as designated by the line 4—4 of Fig. 1.

Referring now to the several figures of the drawing, the reference characters 10 and 11 indicate respectively a stile and top rail of a door, providing for the insertion of a single glass panel for the utmost in visibility. The other stile and bottom rail are of the same construction, except for right hand and left hand and inverted construction. The bottom rail is preferably of a deeper section, so glass is not subjected to striking of feet or hand trucks. A tenon 12, at each end of a rail, engages a mortise 13 in a stile, and is secured by pinning and gluing in the conventional manner. The solid wood core construction is the equivalent of good wood door construction.

To metal sheathe the door, so it has an attractive appearance in keeping with modern store fronts, anodized sheet aluminum is desirable. As the fine surface finish of this material is destroyed by any method involving great heat, and welding it at all is also impossible, it is imperative that the sheathing be secured in some other particular manner. Stainless steel, another desirable material, also presents difficulties in preserving surface finish during welding operations and it is subject to excessive warping. The problem is therefore to completely sheathe the door without application of heat or welding, and accomplish it so that all joints are concealed, so that the door has the appearance of an all metal door. Referring to Fig. 2, which is a cross sectional view of a stile, it will be observed

that a metal sheet 14 is formed to envelop two sides and the outer edge of a stile, and the sheet is formed around the respective corners of the inner edge and secured by nails 15, engaging the wood core. A combination molding and covering strip 16 is secured by nails 17. This conceals one row of the nails 15 and provides the outside molding strip for a glass panel 18. The inside molding strip 19 is secured by screws 20, engaging the wood core. This strip covers the row of nails 17 and a row of the nails 15 in addition to serving as the inside molding strip for the glass panel 18. When the stile is completed by the installation of this molding strip, no joining or fastening is visible except the screws 20.

With the screw attached molding strip on the inner side and the outer molding strip secured as shown, it is impossible for burglars to remove the glass and make entry.

By referring to Fig. 3, which is a cross sectional view of the top rail, it will be noted that except

for the top edge, the sheathing is accomplished in the same manner as for the stile. At the top edge, a strip of sheet is formed into a channel 21 and secured with nails 22, engaging the wood core. The sheets on the sides of the top rail are bent inwardly and downwardly, to form locking joints 23 over the upwardly extending legs of the channel 21. To provide a flush and finished construction, an inverted channel 24 is placed with a close fit into the recess, formed along the top edge of the door, and secured by screws 25, engaging the wood core. The sheathing and molding for the bottom rail is formed in the same manner, except for the inverted position and greater width of bottom rail.

From the foregoing, it is apparent how the stiles and rails are constructed and how the moldings secure the glass panel in place. These moldings might be mitered at the corners but the square end construction, as shown in Fig. 1, is preferred. At the juncture of the rails with the stiles, a groove 26 is provided on each side for the full width of the rail, into which flanged edges 27 of the sheets, covering respectively the rails and stiles, are fitted. This provides a smooth finished construction, and with the locking joints 23 is very secure. As will be noted from Fig. 4, the end of the sheet sheathing the stile also has locking joints 23 engaging the legs of the channel 21. To facilitate in the manufacture and forming, these locking joints are terminated a short distance from the edge of the stile. In all respects, the joining is similar at all four corners of the door. No difficulty is experienced due to expansion and contraction with this construction. The wood core is made of thoroughly kiln dried lumber and painted with a priming coat. Being so well sheathed with metal, moisture is kept out of the wood, so there is no swelling or shrinking. Since the metal covering is light and secured at close intervals to the wooden core, any tendency of expansion and contraction, due to temperature changes, is overcome. The glass panel is well set in putty around its edge, which takes care of any expansion and contraction of the glass and seals out water and draft.

In providing an entrance type door with a neat, attractive appearance and good visibility, it is apparent that my door has many advantages. It is light, strong, fire resisting, low in cost, and if damaged, can be disassembled and repaired. It meets a great need in the present day modernization of store fronts.

While I have shown and described a preferred form of my invention, it is obvious that many changes, which are within the scope of my invention, will be apparent to those skilled in the art. I therefore desire to be limited only by the scope of the appended claim.

What I claim is:

A sheet metal covered door, comprising stiles and rails of wood of rectangular cross-section, means for uniting said stiles and rails at the corners to form a frame, a sheet metal covering

enveloping each of said stiles and rails, said covering consisting of metal of fine surface finish susceptible to damage by welding and soldering and requiring securement by nails and screws, 5 said door being characterized by progressively concealed nailing and fastening concluded by neat screw fastening, so that an appearance of an all metal door results; said metal covering comprising a sheet enveloping the sides, outside 10 edge and portions of the inner edge of each stile, a pair of sheets covering the sides, portions of the inner edge and extensions beyond the outside edge of each rail; a pair of sheet metal moldings of channel-like cross sectional form, 15 adapted to fit within said frame, to secure a glass panel therebetween, said moldings having their open sides against the inner edges of said frame, and one of said moldings having a flange extending under the edge of said glass panel, said metal covering having an opening of a width to accommodate said flange in positioning itself against said frame, nails securing said flange and the edges of said metal covering to said frame, said moldings concealing the nails in said covering 20 sheets, and one of said moldings also concealing the nailing in said flange of the other molding, and of itself being removably secured by screw fasteners; said outside edges of said rails being provided with a metal covered construction, comprising a channel shaped member with its back nailed to said edge and its legs extending outwardly, said extensions of said sheets extending beyond the edges of said rails and being shaped to extend over said legs and being returned in 25 parallel relation thereto, to form locking joints, and a second channel-shaped member in inverted position having a close fit into the space between said locking joints and secured with screws into the wood frame, resulting in flush edge construction; said stiles and rails having a 30 groove at their junctures and their respective metal side coverings having flanged edges engaging said groove, resulting in a smooth joint.
